COMBINATION ROPE SOCKET AND JAR

Russell Oran Heater, Cary, N. C.

Application January 13, 1940, Serial No. 313,791

2 Claims. (Cl. 255—27)

The present invention relates to new and useful improvements in well drilling devices, and more particularly to a combination rope socket and jar or jarring attachment for well drilling tools, and has for its primary object to provide a device of this character wherein the rope socket and jarring tool are combined as one unit.

Another object of the invention is to provide a tool which eliminates the necessity of using a swivel socket and set of jars and thereby eliminate a great deal of expense of these two separate tools.

Another object of the invention is to provide a combination swivel socket and jar which will cause the drill stem and bit to turn more freely in the hole, thereby drilling straighter holes.

Other objects of the invention are to provide a device of the aforementioned character which will be strong and reliable in use, comparatively light in weight and which may be manufactured at low cost.

Still other objects and advantages of the invention will become apparent from a study of the following detailed description, taken in connection with the accompanying drawing, wherein like characters of reference designate corresponding parts through the several views, and wherein:

Figure 1 is a vertical transverse sectional view of the device embodying my invention.

Figure 2 is a vertical transverse sectional view of the rope socket portion of the jar.

Figure 3 is a transverse sectional view taken substantially on the line 3—3 of Figure 2.

Figure 4 is a transverse sectional view taken substantially on the line 4—4 of Figure 1.

Referring now to the drawing, in detail, it will be seen that the reference numeral 5 designates a tube constructed of metal or other suitable material, and provided with apertures 6, 7 and 8.

40 Mounted in the upper end portion of the tube 5 and secured therein as by welding or otherwise, as at 9, is a rope receiving plug 10 having a bore 11 therethrough which is enlarged at the bottom end of the plug as shown in Figs. 1 and 2 of the drawing. The plug 10 further has a transverse opening 12 therein which aligns with the opening 8 in the tube 5. A shoulder is provided within the tube 5 at the bottom end thereof which is constructed by inserting two sections of a split ring 13 therein and welding the same thereto as shown at 14.

A drill coupling 15 having a threaded socket 16 at its lower end portion for engagement with a drill, is slidably engaged in the tube 5 with its headed portion 17 within the chamber 18 and se-

cured to the socket 16 by the shank 19. The drill coupling 15 is provided with a square intermediate portion 20 between the shank 19 and socket 16 in order that the socket 16 may be turned by a wrench when attaching the same to the drill. 5

When the rope 21 is attached to the device one end of the rope is inserted in the bore 11 and is thereafter expanded in some conventional manner in the lower end of the bore after which operation suitable sealing means, such as putty, is inserted through the opening 7 to seal off the rest of the chamber 18. After the putty has been put in place molten lead or other suitable metal is poured through the aligned openings 8 and 12 and is allowed to harden or solidify about the 15 expanded end portion of the rope 21 to anchor the same within the bore 11.

When the device is operated to jar a tool attached in the socket 16 the tube 5 is reciprocated to permit the lower end of the tube to contact 20 and hammer against the shoulder 22 in one direction and against the head 17 in an opposite direction. When the device is operating in this manner any water or other fluid within the chamber 18 is permitted to escape therefrom through the 25 openings 6 and 7. As can be seen, the head 17 and shank 19 are permitted to freely rotate in the tubular member 5 and thus provide a swivel connection between the tubular portion 5 and the drill engaging member 15. 30

Although I have shown and described herein a preferred embodiment of my invention, it is to be definitely understood that I do not desire to limit the application of the invention thereto, and any change or changes may be made in the materials 35 and in the structure and arrangement of the parts, within the spirit of the invention as claimed.

What is claimed is:

1. A combined socket and jar comprising an 40 elongated perforated cylinder, a shank having a head on its upper end slidably arranged in the cylinder, a sectional sleeve fastened in the lower end of the cylinder and through which the shank passes, the upper end of the sleeve forming a 45 shoulder for engagement by the head, a bored plug having a lower portion fastened in the upper portion of the cylinder, the lower end of the bore of the plug being enlarged to receive an enlarged end of a cable passing through the bore of the 50 plug, that part of the cylinder between the lower end of the plug and the upper end of the sleeve forming a chamber through which the head of the shank moves, some of the perforations forming drain openings for the chamber and the lower 55

part of the plug having a transverse opening therein registering with a perforation in the cylinder and in communication with the enlarged part of the bore for permitting material to be introduced into the large part of the bore to hold the cable end therein.

2. A combined socket and jar comprising an elongated cylinder having perforations therein, a shank having a head at its upper end, a sectional sleeve fitting in the lower end of the cylinder and surrounding the shank with its upper end forming a shoulder for engagement by the lower end

of the head, said sleeve being welded in the lower end of the cylinder, a socket member connected with the lower end of the shank and the upper part of the socket member being of non-circular shape in cross section to receive a wrench, a bored plug having its lower part fitting in the upper part of the cylinder and welded in the cylinder, the lower end of the bore being enlarged to receive an enlarged end of a cable having a portion passing through the bore. 10
